(57) **CLAIM**

The ornamental design for a transparent anchor for wall or ceiling, as shown and described.

DESCRIPTION

FIG. 1 is a top front left perspective view of a transparent anchor for wall or ceiling;

FIG. 2 is a front elevational view of the transparent anchor for wall or ceiling;

FIG. 3 is a left-side elevational view of the transparent anchor for wall or ceiling; the right-side elevational view is a mirror image thereof;

FIG. 4 is a rear elevational view of the transparent anchor for wall or ceiling;

FIG. 5 is a top plan view of the transparent anchor for wall or ceiling;

FIG. 6 is a bottom plan view of the transparent anchor for wall or ceiling; and,

FIG. 7 is a cross-sectional view of the transparent anchor for wall or ceiling, taken along the plane indicated by lines 7-7 of FIG. 2.

The broken lines in the drawings illustrate portions of the transparent anchor for wall or ceiling and form no part of the claimed design.

1 Claim, 3 Drawing Sheets
